(57) **CLAIM**

The ornamental design of a utility trailer, as shown and described.

DESCRIPTION

FIG. 1 is a front perspective view of a utility trailer in accordance with the new design;

FIG. 2 is a right side view of the utility trailer;

FIG. 3 is a left side of the utility trailer of FIG. 1;

FIG. 4 is a front end view of the utility trailer of FIG. 1;

FIG. 5 is a rear end view of the utility trailer of FIG. 1;

FIG. 6 is a top plan view of the utility trailer of FIG. 1; and,

FIG. 7 is a bottom plan view of the utility trailer of FIG. 1.

In the drawings, the broken lines depict portions of a utility trailer and form no part of the claimed design.
